HIS ATTORNEY

UNITED STATES PATENT OFFICE.

THOMAS J. REED, OF BRIDGEPORT, CONNECTICUT, ASSIGNOR TO UNION TYPEWRITER COMPANY, OF JERSEY CITY, NEW JERSEY, A CORPORATION OF NEW JERSEY.

TYPE-WRITING MACHINE.

No. 893,373.

Specification of Letters Patent.

Patented July 14, 1908.

Application filed August 13, 1907. Serial No. 388,283.

To all whom it may concern:

Be it known that I, THOMAS J. REED, citizen of the United States, and resident of Bridgeport, in the county of Fairfield and State of Connecticut, have invented certain new and useful Improvements in Type-Writing Machines, of which the following is a specification.

My invention relates to carriage stop mechanism for typewriting machines and more particularly to tabulator stop devices.

One object of my invention is to provide simple stop devices that are strong in construction and that efficiently resist the shock on the stop and yet in which the stop occupies but little space, may be readily adjusted on the carriage and is not expensive to manufacture.

A further object of my invention is to provide simple and efficient means for preventing the accidental detachment of the stops from the stop bar.

To the above and other ends which will hereinafter more clearly appear, my invention consists of the features of construction, arrangements of parts and combinations of devices to be set forth in the following specification and particularly pointed out in the appended claims.

In the drawings, Figure 1 is a detail fragmentary top plan view showing the stop bar with the stops mounted in place thereon, a coöperating stop, and means for mounting the stop bar in place on the machine. Fig. 2 is an enlarged detail transverse sectional view taken through the stop bar on the line $x-x$ of Fig. 3 and looking in the direction of the arrow at said line. Fig. 3 is an enlarged detail front elevation showing a portion of the stop bar and a stop mounted in place thereon, the view showing the parts as seen from the direction of the arrow a in Fig. 2. Fig. 4 is an enlarged detail sectional view of the parts, the section being taken on the line $y-y$ of Fig. 2 and looking in the direction of the arrow at said line.

The stop bar 1 may be secured to arms 2 which project either from the frame of the machine or from the carriage. In the present instance I have shown the stop bar carried by arms which are intended to be secured to the carriage so that the stop bar travels therewith as in the No. 6 Remington

machine. The stop bar is preferably rectangular in cross section as shown in Fig. 2 and 55 may be provided with the usual scale on the top of the bar as indicated in Fig. 1. The bar is provided with teeth 3, 4 on opposite sides thereof, the teeth 3 being on the rear side of the bar and the teeth 4 on the front 60 side thereof. Each of these teeth is beveled or inclined on one face 5 and is abrupt or at right angles to the axis of the bar on the opposite face 6 thereof. The inclined or beveled faces 5 of the teeth on opposite sides of 65 the bar are on opposite sides of the teeth; thus the bevel of each of the teeth 3 is situated on the right-hand side of the tooth, whereas the bevel or inclined face of each tooth 4 is on the left-hand side thereof. The 70 purpose of this particular arrangement of the teeth will be hereinafter explained. Detachable column stops 7 are preferably made of sheet metal and each forms a plate-like bifurcated stop which is adapted to straddle the 75 stop rod and to be adjusted from one position thereon to another. Each of the stops 7 has arms 8 and 9 with an opening 10 between them by which they are enabled to straddle the rod. The wall of the opening 10 on the 80 arm 8 is beveled at 11 to match the beveling of the teeth 3 on the rear of the rod, whereas the flat face 12 of the stop co-acts with the abrupt sides of the teeth. The opposite wall of the opening 10 on the arm 9 of the 85 stop has an oppositely disposed beveled face 13 to match the bevels of the teeth 4, the straight or flat side 14 of the stop co-acting with the abrupt faces of the teeth 4. The walls of the opening 10 are therefore shaped 90 to form teeth which match and co-act with the teeth on opposite sides of the stop bar. By beveling the engaging walls of the column stops and the teeth of the stop bar in the manner described I am enabled to make the 95 column stops of heavier stuff and to provide a stronger construction than where square teeth are formed on the stop rod to receive the plate-like bifurcated column stops between the teeth. Thus from an inspection 100 of Fig. 4 it will be seen that the distance from the abrupt face of one tooth to that of an adjacent tooth indicated by the dotted lines a , b , may be taken as the distance between two teeth. It will be observed that in the present instance the column stop is of such thick- 105

ness as to occupy most of the space between these two lines and that nevertheless the teeth are not weakened, but that on the contrary the base of the tooth also occupies most of the space between the lines *a*, *b*. The effect of this construction, therefore, is to provide strong and durable stop devices which efficiently resist the impact on the column stops.

10. By beveling the teeth on opposite sides of the stop bar on opposite faces thereof and correspondingly beveling the engaging portions of the column stops, I attain a still further advantage in resisting the impact on the 15 column stops, as will appear from the following description. The arm 8 of each stop 7 co-acts with the coöperating stop 15 so that when the stop 15 is projected into the path of the stop 7 as shown in Figs. 1 and 4, the impact on the stop 7 will be resisted by the abrupt faces of the engaged teeth on opposite sides of the stop bar co-acting with the flat faces 12 and 14 of the stop, and there is no tendency of the co-acting beveled faces of 20 the stop and stop bar teeth to displace the column stops or to spread the bifurcated arms 8, 9 thereof apart, the flat face of the engaged tooth on the rear side of the bar resisting the impact of the stop in one direction and the flat face of the engaged tooth on the front of the bar resisting the impact of the stop in an opposite direction. The force of the impact comes on the abrupt face of one 25 of the teeth 4 and on the abrupt face of one of the teeth 3, none of said force coming on the inclined faces of the teeth. It will be seen, therefore, that I have provided simple strong and efficient stop devices, each of the 30 stops being formed of a single piece of sheet metal and yet efficiently resisting the impact thereon.

In order to provide against the accidental displacement of the column stops from the stop bar I have provided a retaining device 45 which is in the nature of a wire spring, the body portion 16 of which is situated against one face of the column stop on the arm 9 thereof and extends in a plane parallel to the plane of the stop. The ends of the wire 50 spring are bent at right angles to the body portion thereof and are projected through apertures 17 which extend through the plate-like stop and the extreme terminal portions 18 of the wire are bent over against the opposite face of the stop in order to secure said wire in place on the stop. The body portion 55 16 of the spring is formed intermediate the ends thereof with a bend which forms a projection 19 adapted to engage beneath a corner or edge 20 of the stop bar as shown in Fig. 2. This edge of the bar is in effect a corner of one of the teeth engaged by the stop which carries the spring as indicated in Fig. 4. The projection 19 engages under the 60 corner of the tooth in the manner described 65

and prevents the column stop from being accidentally displaced transversely of the bar, and yet enables it to be readily removed when desired in order to change the position of the stop along the bar, the spring wire 70 yielding when the stop is forced on or off of the bar.

Various changes may be made without departing from the spirit and scope of my invention.

What I claim as new and desire to secure by Letters Patent, is:

1. In a carriage stop construction for typewriting machines, the combination of a stop bar having teeth on opposite sides thereof, each tooth having a beveled face and an abrupt face, the bevels of the teeth on opposite sides of the bar being oppositely disposed, and a stop with teeth shaped to engage in the openings between the teeth on 85 said bar.

2. In a carriage stop construction for typewriting machines, the combination of a stop bar having teeth on opposite sides thereof, each tooth having a beveled face and an abrupt face, the bevels of the teeth on opposite sides of the bar being oppositely disposed and a detachable bifurcated stop, the walls of the bifurcation forming teeth which fit and are received in the spaces between the 95 teeth on opposite sides of the stop rod.

3. In a carriage stop construction for typewriting machines, the combination of a stop bar having teeth on opposite sides thereof, each tooth having a beveled face and an abrupt face, the bevels of the teeth on opposite sides of the bar being oppositely disposed and a sheet metal detachable stop bifurcated to straddle said stop bar, opposite walls of the opening in the stop formed by 100 the bifurcation matching the teeth on opposite sides of the stop bar.

4. In a carriage stop construction for typewriting machines, the combination of a stop bar having teeth on opposite sides thereof, each tooth having a beveled face and an abrupt face, the bevels of the teeth on opposite sides of the bar being oppositely disposed and a flat-metal plate-like detachable stop of a single thickness of metal with teeth 110 thereon which match the teeth on opposite sides of the stop bar.

5. In a carriage stop construction for typewriting machines, the combination of a stop bar having teeth, a flat plate-like stop 120 detachably secured to said stop bar, and a spring secured to said stop and projecting from one of the flat sides thereof and engaging directly under one edge or corner of the bar to prevent an accidental detachment of 125 the stop from the bar.

6. In a carriage stop construction for typewriting machines, the combination of a stop bar having teeth, a stop detachably secured to said stop bar, and a spring secured 130

at both ends to said stop and having a projection intermediate its ends, said projection engaging under one edge or corner of the bar to prevent the accidental detachment of the 5 stop from the bar.

7. In a carriage stop construction for typewriting machines, the combination of a stop bar having teeth, a stop detachably secured to said stop bar, said stop having perforations therein, and a wire spring secured 10 at its ends in said perforations and having an intermediate portion which engages said stop bar and prevents the accidental displacement of the stop from the bar.

15 8. In a carriage stop construction for typewriting machines, the combination of a stop bar having teeth, a flat plate-like sheet-metal stop bifurcated to straddle said bar and engage the teeth thereon, and a spring 20 which is connected to said stop and projects from one of the flat sides thereof, the body of the spring extending in a plane parallel to the plane of the stop and directly engaging the bar to prevent accidental displacement 25 of the stop from the bar.

9. In a carriage stop construction for typewriting machines, the combination of a stop bar having teeth, a plate-like sheet metal stop bifurcated to straddle said bar and engage 30 the teeth thereon, and a spring which is connected to said stop at one side thereof, the body of the spring extending in a plane parallel to the plane of the stop and having a projection formed by a bend in the spring, 35 said projection engaging under a corner or edge of the bar and preventing an accidental displacement of the stop from the bar.

10. In a carriage top construction for typewriting machines, the combination of a stop bar having teeth on opposite sides 40 thereof, each tooth having a beveled face and an abrupt face, the bevels of the teeth on opposite sides of the bar being oppositely disposed, a stop with teeth shaped to engage in the openings between the teeth on 45 said bar, and a spring carried by said stop and engaging under the corner of one of the engaged teeth on said bar to prevent an accidental displacement of the stop from said 50 bar.

11. In a carriage stop construction for typewriting machines, the combination of a stop bar having teeth on opposite sides thereof, each tooth having a beveled face 55 and an abrupt face, the bevels of the teeth on opposite sides of the bar being oppositely disposed, a sheet metal plate-like detachable stop bifurcated to straddle said stop bar, opposite walls of the opening in the stop formed 60 by the bifurcation matching the teeth on opposite sides of the stop bar, the abrupt faces of the engaged teeth on the bar resisting the shock on the stop, and a wire spring secured at its ends in perforations in said stop and the body portion of the spring being situated in a plane parallel with the plane of the stop and having a projection formed by a bend in the spring, said projection engaging under a corner of one of the engaged teeth of the 65 stop bar and preventing an accidental displacement of the stop from the bar.

bar to prevent the accidental displacement of the stop from the bar.

12. In a carriage stop construction for typewriting machines, the combination of a stop bar having teeth on opposite sides 70 thereof, each tooth having a beveled face and an abrupt face, the bevels of the teeth on opposite sides of the bar being oppositely disposed, a sheet-metal detachable stop bifurcated to straddle said stop bar, opposite 75 walls of the opening in the stop formed by the bifurcation matching the teeth on opposite sides of the stop bar, and a spring secured at both ends to said stop and having a projection intermediate its ends, said projection 80 engaging under one edge or corner of an engaged tooth on the bar and preventing an accidental detachment of the stop from the bar.

13. In a carriage stop construction for typewriting machines, the combination of a stop bar having teeth on opposite sides thereof, each tooth having a beveled face and an abrupt face, the bevels of the teeth on opposite sides of the bar being oppositely 90 disposed, a sheet metal detachable stop bifurcated to straddle said stop bar, opposite walls of the opening in the stop formed by the bifurcation matching the teeth on opposite sides of the stop bar, said stop having 95 perforations therein, and a wire spring secured at its ends in said perforation and having an intermediate portion which engages one of the engaged teeth on the stop bar and prevents an accidental displacement of the 100 stop from the bar.

14. In a carriage stop construction for typewriting machines, the combination of a stop bar having teeth on opposite sides thereof, each tooth having a beveled face 105 and an abrupt face, the bevels of the teeth on opposite sides of the bar being oppositely disposed, a sheet metal plate-like detachable stop bifurcated to straddle said stop bar, opposite walls of the opening in the stop formed 110 by the bifurcation matching the teeth on opposite sides of the stop bar, the abrupt faces of the engaged teeth on the bar resisting the shock on the stop, and a wire spring secured at its ends in perforations in said stop and the body portion of the spring being situated in a plane parallel with the plane of the stop and having a projection formed by a bend in the spring, said projection engaging under a corner of one of the engaged teeth of the 115 stop bar and preventing an accidental displacement of the stop from the bar.
